UNITED STATES PATENT OFFICE.

MOAD H. LE MARR, OF LOS ANGELES, CALIFORNIA.

SAFETY-CATCH FOR PINS AND BROOCHES.

1,386,574.

Specification of Letters Patent.

Patented Aug. 2, 1921.

Application filed August 25, 1920. Serial No. 405,952.

To all whom it may concern:

Be it known that I, MOAD H. LE MARR, a citizen of the United States, residing at Los Angeles, in the county of Los Angeles 5 and State of California, have invented new and useful Improvements in Safety-Catches for Pins and Brooches, of which the following is a specification.

This invention relates to safety catches 10 for pins and brooches.

It is the object of the invention to provide a safety catch which may be readily formed from a suitable stamped metal blank and a coöperating retaining member also stamped 15 from a metal blank. The invention will be readily understood from the following description of the accompanying drawings, in which—

Figure 1 is a side elevation of a pin having the improved safety catch.

Fig. 2 is an end view of the same.

Fig. 3 is a plan view of the blank from which the catch is constructed.

Fig. 4 is an edge view of the folded blank 25 forming the catch.

Fig. 5 is a side elevation of the folded catch.

Fig. 6 is an edge view of the same taken from the opposite direction to that of Fig. 4.

Fig. 7 is a section on line 7—7 of Fig. 5.

Fig. 8 is a plan view of the retaining member.

Fig. 9 is an edge view of the same.

Fig. 10 is a longitudinal section through 35 the catch, showing the retaining member in position with relation to the same.

Fig. 11 is a similar view showing the retaining member in closed position.

Fig. 12 is a section on the line 12—12 of 40 Fig. 10.

The improved safety catch is shown employed in connection with a bar pin consisting of bar 1 having the pin 2 extending lengthwise thereof and pivoted to the bar 45 at the pivot 3. The safety catch is mounted upon bar 1 so as to engage the swinging pointed end 4 of the pin.

The safety catch consists of a catch member forming a hook adapted to engage the 50 pin and a retaining member pivoted with relation to the catch member so as to either close or leave open the end of the hook past which the pin is adapted to move.

The catch is formed from a blank preferably having a straight lower edge 6 and side edges curved at their upper ends in-

wardly and then downwardly as shown at 7. A substantially heart shaped opening 8 is provided in the blank, said opening forming a depending lip 9 at the medial line of 60 the blank and hook-shaped portions 10 extending in opposite directions from the medial line of the blank and terminating in side uprights 11 which extend to the lower edge 6 of the blank. Depressions 12 are 65 provided in the respective hook-shaped portions 10 of the blank, and a projection 13 is formed in one of the side uprights of the blank, preferably at the side edge thereof.

The blank as thus constructed is adapted 70 to be folded upon its medial line as shown in Fig. 4 so that the side uprights 12 overlie one another and are spaced apart by the projection 13 of one side upright abutting against the opposite side upright. The lip 75 9 and the hook-shaped portions 10 of the blank will thus form a hook having the recess 14 adapted to receive the pin 2, the open portion of said hook being formed at 15 between the end of lip 9 and the side uprights 11. When the blank is thus folded 80 the depressions 12 is brought into transverse spaced alinement in order to provide bearings.

The retaining member employed in connection with the catch member as thus constructed consists of a flat metal blank having bearing pins 17 projecting from the opposite surfaces thereof at one end of the blank. The blank is curved from the end carrying pins 90 17 in order to form a recess 18 adapted to fit around the pin 2 received in the recess of the catch member, and at its opposite end said blank terminates in an end retaining lug 19 adapted to be positioned across the 95 opening 15 of the catch member. A recess 20 is provided in the edge of the retaining member opposite the edge thereof forming recess 18 and a projection 21 adapted to be engaged by the finger is preferably also 100 formed upon said edge of the blank between pivot pins 17 and the recess 20.

In assembling the parts the retaining member is positioned with relation to the blank forming the catch member with one of 105 its pivot pins 17 in one of the bearing depressions 12 and the catch member is then folded over the retaining member as previously described, the retaining member being positioned within the fold of the catch 110 member so that recess 18 coöperates with recess 14 to provide an aperture through which

pin 2 may extend. The parts are so proportioned that when the retaining member is swung rearwardly as shown in Fig. 10, the lug 19 will leave open the opening 15 of the 5 catch so that the pin 2 may be readily inserted within recess 14 formed by the hook of the catch. The rearward swing of the retaining member is limited by abutment of lug 19 against projection 13. The pin 2 10 having been positioned within the recess of the catch, the retaining member is swung forwardly and lug 19 will then form a closure for the opening 15. As the retaining member is thus swung forward, recess 20 15 will be engaged by projection 13 in order to provide yieldable means for holding the retaining member in locking position. When it is again desired to open the catch the retaining member may be swung rearwardly 20 by applying sufficient pressure thereto to disengage projection 13 from recess 20.

Various changes may be made without departing from the spirit of the invention as claimed.

25. What is claimed is:

1. A safety catch for pins and brooches comprising a blank folded upon itself to form a hook, bearings pressed in the parts of the blank above the hook-shaped portion 30 thereof, a retaining member pivoted in said bearings so as to swing into and out of position between the parts of the folded blank, said retaining member having a portion that is adapted to close the opening into the hook,

and a projection pressed inwardly from one 35 of the parts of the blank below said hook for engaging said pivoted member to hold the same in position to close the opening into said hook.

2. A safety catch for pins and brooches 40 comprising a blank folded upon itself to form a hook, bearings pressed in the parts of the blank above the hook-shaped portion thereof, a retaining member pivoted in said bearings so as to swing into and out of position 45 between the parts of the folded blank, said retaining member having a portion that is adapted to close the opening into the hook, a projection pressed inwardly from one of the parts of the blank for engaging said pivoted member to hold the same in position to close the opening into said hook, and a projection on the rear side of said hook closing member whereby the latter may be moved into and out of hook closing position. 50

3. A safety catch including a blank folded upon itself to form a hook, said folded blank having a depression forming a projection extending between the folds of said hook, and a retaining member pivoted between the 60 folds of said hook and adapted to be swung into position for closing the opening of said hook, said retaining member being engaged by said projection in open or closed position. 65

In testimony whereof I have signed my name to this specification.

MOAD H. LE MARR.
